UNDERFRAME

William C. Hedgecock, Wilmette, and Robert B. Cottrell, Chicago, Ill., assignors to American Steel Foundries, Chicago, Ill., a corporation of New Jersey

Application December 13, 1933, Serial No. 702,152

20 Claims. (Cl. 105—414)

This invention pertains to car underframes and more particularly to a four-wheel car underframe provided with outboard type of wheel and axle assemblies.

5 It is an object of this invention to provide a cast steel underframe or a fabricated underframe adapted particularly for use with a four-wheel car having outboard wheel and axle assemblies.

Still another object of the invention is to provide 10 a car underframe with combined cast steel cross bearer and journal box pedestal jaws adapted for four-wheel freight cars using various types of spring suspensions.

A yet further object of this invention is to 15 provide a novel construction of pedestal jaws for use on four-wheel cars and particularly a pedestal jaw designed to accommodate various spring combinations.

It is also an object of this invention to provide 20 a novel form of pedestal jaw designed particularly for application to a four-wheel car underframe structure.

With these and other objects in view the invention may consist of certain novel features of construction and operation as will be more fully described and particularly pointed out in the specification, drawings and claims appended hereto.

In the drawings, which illustrate embodiments 25 of the device and wherein like reference characters are used to designate like parts—

Figure 1 is a fragmentary top plan view of an integrally formed cast steel underframe embodying the invention;

Figure 2 is a fragmentary side elevation of the 30 car illustrated in Figure 1;

Figure 3 is a transverse fragmentary sectional elevation taken substantially in the plane as indicated by the line 3—3 of Figure 2;

Figure 4 is an enlarged transverse sectional 35 elevation of the spring pocket taken substantially in the plane as indicated by the line 4—4 of Figure 2;

Figure 5 is a fragmentary top plan view of a modified form of car underframe construction 40 embodying the invention;

Figure 6 is a fragmentary side elevation of the truck construction shown in Figure 5;

Figure 7 is a transverse fragmentary sectional elevation taken substantially in the plane as 45 indicated by the line 7—7 of Figure 5;

Figure 8 is a fragmentary top plan view of another modified form of car underframe construction embodying the invention;

Figure 9 is a fragmentary side elevation of the 50 underframe construction illustrated in Figure 8;

Figure 10 is a transverse fragmentary sectional elevation taken substantially in the plane as indicated by the line 10—10 of Figure 8;

Figure 11 is a fragmentary top plan view of a car underframe construction such as illustrated 5 in Figure 8 showing the same adapted for use with another form of spring suspension;

Figure 12 is a fragmentary side elevation of the car underframe construction illustrated in Figure 11;

Figure 13 is a fragmentary transverse sectional elevation as indicated by the line 13—13 of Figure 11;

Figure 14 is a fragmentary side elevation of the car underframe construction illustrated in Figure 1 showing a different form of spring suspension;

Figure 15 is a fragmentary side elevation of the car underframe construction illustrated in Figure 8 having a different spring arrangement applied thereto;

Figure 16 is a fragmentary side elevation of a car underframe construction such as illustrated in Figure 8 showing still another spring arrangement applied thereto.

In the car underframe constructions illustrated 25 in Figures 1 to 7 inclusive and 14, an integral cast steel type of frame is shown including the end sills 20 having the striking casting 22 cast integral therewith and provided with the draft gear pocket 24. The draft gear pocket includes 30 the spaced draft sills 26 provided with front and rear draft lugs 28 and 30 respectively, and transverse means in the form of spaced members 32 disposed in spaced relation to the ends of the sills and being substantially aligned with a transverse 35 cross bearer referred to hereinafter.

In the construction illustrated in Figures 1 to 4 inclusive, spaced center sills 34 are disposed substantially in alignment with the spaced draft sills 26.

In the construction illustrated in Figures 5 to 7 inclusive, the draft sills 26 are suitably connected as by means of the riveting 38 to the spaced center sills 40 whereby the center sills are in substantial alignment with the draft sills 26.

In each construction the transverse cross bearer 42 is integrally formed with the draft and center sills and extends transversely of the truck intersecting the spaced pedestal sills 44, the outer transverse beam portion 46 of the cross bearer 50 being suitably connected as at 48 to the side sills 50, said sills being also connected to the outer end beam portion 52 as at 54.

Again, in the construction illustrated in Figures 5 to 7 inclusive, pedestal sill brackets 56 are pro- 55

vided for connection as at 58 to separate pedestal sill members 60 disposed in longitudinal alignment with the integral pedestal sills 44 thereof. The diagonal brace member 62 is integrally formed with the end sills and pedestal sills and extends diagonally inwardly to merge with the draft sills 26, adjacent the cross bearer 42.

Referring now more particularly to the under-frame spring suspension illustrated in Figures 1 to 4 inclusive, the pedestal sills are provided with pedestals 64, including the spaced pedestal jaws 66, said jaws including the spaced plates 68. The pedestal jaws slidably receive the journal box 70, said journal box having cooperative relation with the journal ends of the wheel and axle assembly 72. Suitable wear plates 74 are provided on said jaws for accommodating the wear due to relative movement of the journal box in respect to the pedestals, the retainer plate 76 being connected across said jaws for preventing disassociation of the journal box and said pedestals.

The journal box is provided with the upper leaf spring seat 78 for receiving the spring band 80 of the semi-elliptic leaf spring assembly 82. One leg 84 of said leaf spring assembly is adapted to be seated in the integral leaf spring seat 86 provided on the pedestal sills between the spaced plate 68 of the pedestals, the leg of said spring being adapted to be positioned by means of the depending dowel 88 received in a suitable aperture provided in said spring. The pedestal sills on the other side of said journal box are provided with the coil spring pocket 90 provided with the coil spring seat 92 in which the coil spring 94 is seated. The other end of said coil spring is seated on the coil spring seat 96, said seat being supported on the other leg 98 of the leaf spring assembly 82, said seat being also provided with a depending positioning dowel 100 received in a suitable aperture provided in the leg 98 of said spring. It will thus be seen that in this construction the underframe is supported partly by springs of different character in series and partly by one leg of the leaf spring.

In the construction illustrated in Figures 5 to 7 inclusive, the pedestal sills 44 are provided with the pedestal 102, including the spaced pedestal jaws 104 having the wear plates 106, journal box retainer 108, and spaced plates 110 forming said jaws. The journal box 112 is adapted to have cooperative relation with the journal ends of the wheel and axle assemblies 114, and has slidable engagement with the wear plates 106 and the pedestals. In this construction the journal box is provided with coil spring seats 116 adapted to accommodate the coil springs 118, the upper ends of said coil springs being seated on the coil spring pedestal seat 120 shown as disposed below the pedestal sills 44 and interposed between the pedestal jaws. The position of the seat is of course to be determined by the height of the spring required.

In Figure 14 the construction is practically the same except that the integral form of under-frame is contemplated as illustrated in Figures 1 to 4 inclusive.

Referring now to the fabricated or built-up type of the underframe illustrated in Figures 8 to 13 inclusive, 15 and 16, the end sill 122 is provided with the separate striking casting 124 secured thereto as at 126, the center sills 128 being connected to the end sill 122 as at 130, the portion of the center sill between the end sill and the cross bearer 132 forming draft sills 134. The

draft sills are provided with the spaced inner and outer draft lugs 136 and 138 and are connected by a plate member 140 which extends from adjacent the lugs 138 at the end of the under-frame shown to adjacent the corresponding lugs 5 at the other end of the underframe. The cross-bearer 132 is interrupted as at 142 to permit the passage of the draft center sill therethrough, the portions of the cross bearer on each side of the draft sill being flanged as at 144 and secured to 10 said center sill as at 146. Pedestal sills 148 also intersect cross bearer 132 and are connected to flanged portions 150 thereof as at 152, and are connected to the end sill as at 154 and to a bracket 156 as at 158. The diagonal brace member 160 is connected to the bracket 156 and to the bracket 162, the last named bracket being connected to the draft sills 134 and cross bearer 132.

Referring now more particularly to the construction illustrated in Figures 8 to 10 inclusive, the pedestal sills are provided with the pedestals 164 suitably secured thereto, said pedestals including the spaced jaws 166, the wear plates 168, the retainer 170 and the coil spring seat 172 disposed between said jaws. The journal box 174 is adapted to have cooperative relation with the journal ends of the wheel and axle assembly 176, said journal box having sliding cooperation with the wear plates. The journal box is provided with the coil spring seats 178 adapted to accommodate the coil springs 180 disposed on said seats 178 and engaging the seats 172 whereby the underframe is resiliently supported on the wheel and axle assemblies.

In the construction illustrated in Figures 11 to 13 inclusive, the pedestals 182 are secured to the pedestal sills 148 and include the spaced jaws 184 provided with the wear plates 186 and the retainer 188. The journal box 190 has cooperative engagement with the journal ends of the wheel and axle assemblies 192 and has sliding cooperation with the wear plates 186. The journal box is provided with the leaf spring seat 194 adapted to receive the lower spring band 196 of 45 the full elliptic leaf spring assembly 198, the upper spring band 200 being seated on the leaf spring seat 202 provided on the pedestal.

In the construction illustrated in Figure 15, the pedestals 204 include the spaced pedestal jaws 206 provided with the wear plates 208 and the journal box retainer 210, and is provided with the spaced integrally formed leaf spring seats 212. The journal box 214 is adapted to have sliding cooperation with the wear plates and has cooperative engagement with the journal ends of the wheel and axle assemblies 216. The journal box is provided with a leaf spring seat adapted to receive the spring band 218 of the semi-elliptic leaf spring assembly 220, the legs of the leaf spring assembly being in supporting relation to the spaced seats 212 and relative upward movement being regulated by means of the stop 222 provided on the pedestal and serving as a brace between the spaced plates forming the pedestal.

In the pedestal arrangement illustrated in Figure 16, the pedestals 224 include the spaced plates 226 suitably connected by means of the straps 228, the pedestals including the spring jaws 230 adapted to slidably receive the journal box 232, the jaws being connected by the retainer 234. The pedestals are not only connected as at 236 to the under side of the pedestal sills 44 but are also connected as at 238 to the web of said 75

pedestal sills through the bracket portion 240 of said pedestals. The journal box is provided with the leaf spring seat 242 adapted to receive the spring band 244 of the semi-elliptic leaf spring assembly 246, the legs of said assembly being in supporting engagement with the spaced leaf spring seats 248 provided on said pedestal between said plates 224.

In each of the fabricated constructions shown in Figures 8 to 13 inclusive, 15 and 16, the transverse beam members 226 are secured to the pedestal sills 148, and the end beam members 227 are provided, said beam members supporting the side sills 228 secured thereto.

It will of course be appreciated that the various spring arrangements shown in applicant Hedgcock's copending application Serial No. 702,151, filed with the present application, may readily be adapted to the underframe construction illustrated in the present application and it will be appreciated that a four-wheel car of easy riding qualities and of simple construction is provided in the present underframe.

It is to be understood that we do not wish to be limited by the exact embodiments of the device shown, which are merely by way of illustration and not limitation, as various and other forms of the device will of course be apparent to those skilled in the art without departing from the spirit of the invention or the scope of the claims.

We claim:

1. In a car underframe structure, the combination of a single piece integral casting including a center sill, said center sill having transverse means disposed in spaced relation to the end thereof, a transverse cross bearer substantially in alignment with said transverse means, an end sill, spaced draft sills disposed between said cross bearer and said end sill, pedestal sills connected to said end sill and cross bearer, and having journal pedestals formed with spaced plates, and a spring seat disposed between said plates and embraced thereby.

2. In a car underframe structure, the combination of a single piece integral casting including a center sill, said center sill having transverse means disposed in spaced relation to the end thereof, a transverse cross bearer substantially in alignment with said transverse means, an end sill, spaced draft sills disposed between said cross bearer and said end sill, pedestal sills connected to said end sill and cross bearer, journal pedestals on said pedestal sills disposed adjacent said cross bearer, said pedestals having spaced plates, and a leaf spring seat disposed between and embraced by said plates.

3. In a car underframe structure, the combination of a single piece integral casting including a center sill, said center sill having transverse means disposed in spaced relation to the end thereof, a transverse cross bearer substantially in alignment with said transverse means, an end sill, spaced draft sills disposed between said cross bearer and said end sill, pedestal sills connected to said end sill and cross bearer and having journal pedestals formed with spaced plates, and a spring seat on each pedestal sill disposed between and embraced by the plates for each of the pedestals.

4. In a car underframe structure, the combination of a single piece integral casting including a center sill, said center sill having transverse means disposed in spaced relation to the end thereof, a transverse cross bearer substan-

tially in alignment with said transverse means, an end sill, spaced draft sills disposed between said cross bearer and said end sill, pedestal sills connected to said end sill and cross bearer, a journal pedestal on said pedestal sills between said cross bearer and end sill, said journal pedestal being formed with spaced plates, and spaced leaf spring seats between said plates.

5. In a car underframe structure, the combination of a single piece integral casting including a center sill, said center sill having transverse means disposed in spaced relation to the end thereof, a transverse cross bearer substantially in alignment with said transverse means, an end sill, spaced draft sills disposed between said cross bearer and said end sill, pedestal sills connected to said end sill and cross bearer, journal pedestals on said pedestal sills, said pedestal sills adjacent said pedestals being provided with a recess forming a coil spring seat, and a leaf spring seat on said pedestal sills spaced from said recess.

6. In a car underframe structure, the combination of a single piece integral casting including a center sill, said center sill having transverse means disposed in spaced relation to the end thereof, a transverse cross bearer substantially in alignment with said transverse means, an end sill, spaced draft sills disposed between said cross bearer and said end sill, pedestal sills connected to said end sill and cross bearer, journal pedestals on said pedestal sills adjacent said cross bearer, said journal pedestals being formed with spaced plates, said pedestal sills having a recess providing a coil spring seat adjacent said pedestals, and a leaf spring seat on said pedestal sills between said plates and spaced from said recess.

7. In a car underframe structure, the combination of a single piece integral casting including a center sill, said center sill having transverse means disposed in spaced relation to the end thereof, a transverse cross bearer substantially in alignment with said transverse means, an end sill, spaced draft sills disposed between said cross bearer and said end sill, pedestal sills connected to said end sill and cross bearer, a diagonal brace member extending between said end and pedestal sills and said draft sills and cross bearer, journal pedestals depending from said pedestal sills and comprising spaced plates, and a leaf spring seat disposed between said plates.

8. In a car underframe structure, the combination of a single piece integral casting including a center sill, said center sill having transverse means disposed in spaced relation to the end thereof, a transverse cross bearer substantially in alignment with said transverse means, an end sill, spaced draft sills disposed between said cross bearer and said end sill, pedestal sills connected to said end sill and cross bearer, a journal pedestal on said pedestal sills between said cross bearer and end sill, a diagonal brace member extending between said end and pedestal sills and said draft sills and cross bearer, said pedestal sills being formed with a recess providing a seat for a coil spring, and a leaf spring seat on said pedestal sills spaced from said recess.

9. In a car underframe structure, the combination of a single piece integral casting including an end sill, a cross bearer, spaced draft sills disposed between said end sill and cross bearer, pedestal sills connected to said end sill and cross bearer, means for attachment to separate longi-

- tudinal sill members, journal pedestals on said pedestal sills, said journal pedestals being formed with spaced plates, and a leaf spring seat disposed between said plates.
5. 10. In a car underframe structure, the combination of a single piece integral casting including an end sill, a cross bearer, spaced draft sills disposed between said end sill and cross bearer, pedestal sills connected to said end sill and cross bearer, means for attachment to separate longitudinal sill members, journal pedestals on said pedestal sills, said journal pedestals being formed with spaced plates, and spaced leaf spring seats disposed between said plates.
10. 11. In a car underframe structure, the combination of a single piece integral casting including an end sill, a cross bearer, spaced draft sills disposed between said end sill and cross bearer, pedestal sills connected to said end sill and cross bearer, means for attachment to separate longitudinal sill members, journal pedestals on said pedestal sills, said pedestal sills adjacent said journal pedestals being provided with a recess providing a seat for a coil spring, and a leaf spring seat on said pedestal sills spaced from said recess.
15. 12. In a car underframe structure, the combination of a single piece integral casting including an end sill, a cross bearer, spaced draft sills disposed between said end sill and cross bearer, pedestal sills connected to said end sill and cross bearer, means for attachment to separate longitudinal sill members, journal pedestals on said pedestal sills formed with spaced plates, said pedestal sills being provided with a recess adapted to receive and seat a coil spring between said plates and a leaf spring seat on said pedestal sills between said plates in spaced relation to said recess.
20. 13. In a car underframe structure, the combination of a single piece integral casting including a center sill, a transverse cross bearer, an end sill, spaced draft sills disposed between said cross bearer and said end sill and substantially centrally with respect to the ends thereof, pedestal sills connected to said end sill and cross bearer between said draft sills and the ends of said cross bearer and end sill, said end sill and cross bearer extending laterally outwardly of said pedestal sills, and side sills connected to said end sill and cross bearer.
25. 14. In a car underframe structure, the combination of a single piece integral casting including a center sill, a transverse cross bearer, an end sill, spaced draft sills disposed between said cross bearer and said end sill and substantially centrally with respect to the ends thereof, a means disposed between said draft sills substantially in alignment with said cross bearer, pedestal sills connected to said end sill and cross bearer between said draft sills and the ends of said cross bearer and end sill, said end sill and cross bearer extending laterally outwardly of said pedestal sills, and side sills connected to said end sill and cross bearer.
30. 15. A car underframe structure comprising integral end castings each comprising an end sill, a cross bearer, spaced draft sills disposed between said end sill and cross bearer and substantially centrally with respect to the ends thereof, pedestal sills connected to said end sill and cross bearer between said draft sills and the ends of said cross bearer and end sill, journal pedestals on said pedestal sills, a plurality of separate sill members disposed between said end castings, and means for connecting said separate sill members to said end castings, certain of said separate sill members being connected to said end sill and cross bearer in spaced relation outwardly of said pedestal sills.
35. 16. A car underframe structure comprising integral end castings each comprising an end sill, a cross bearer, spaced draft sills disposed between said end sill and cross bearer and substantially centrally with respect to the ends thereof, pedestal sills connected to said end sill and cross bearer between said draft sills and the ends of said cross bearer and end sill, said castings having members extending laterally of said cross bearer substantially in alignment with said draft and pedestal sills, a plurality of separate sill members extending between and connected to said first-named members and to said cross bearer in spaced relation outwardly of said pedestal sills.
40. 17. A car underframe structure comprising integral end castings each comprising an end sill, a cross bearer, spaced draft sills disposed between said end sill and cross bearer and substantially centrally with respect to the ends thereof, pedestal sills connected to said end sill and cross bearer between said draft sills and the ends of said cross bearer and end sill, said castings having members extending laterally outwardly of said pedestal sills, and a plurality of separate sill members extending between and connected to said first-named members and to said cross bearer and end sill extensions.
45. 18. A car underframe structure comprising integral end castings each comprising an end sill, a cross bearer, spaced draft sills disposed between said end sill and cross bearer and substantially centrally with respect to the ends thereof, pedestal sills connected to said end sill and cross bearer between said draft sills and the ends of said cross bearer and end sill, journal pedestals on said pedestal sills, a plurality of separate sill members disposed between said end castings, and means for connecting said separate sill members to said end castings, certain of said separate sill members being connected to said end sill and cross bearer in spaced relation outwardly of said pedestal sills.
50. 19. A car underframe structure comprising integral end castings each comprising an end sill, a cross bearer, spaced draft sills disposed between said end sill and cross bearer and substantially centrally with respect to the ends thereof, pedestal sills connected to said end sill and cross bearer between said draft sills and the ends of said cross bearer and end sill, journal pedestals on said pedestal sills, said castings having members extending laterally of said cross bearer substantially in alignment with said draft and pedestal sills, and a plurality of separate sill members extending between and connected to said first-named members, and separate sill members connected to said end sill and cross bearer in spaced relation outwardly of said pedestal sills.
55. 20. A car underframe structure comprising integral end castings each comprising an end sill, a cross bearer, spaced draft sills disposed between said end sill and cross bearer and substantially centrally with respect to the ends thereof, pedestal sills connected to said end sill and cross bearer between said draft sills and the ends of said cross bearer and end sill, a plurality of separate sill members disposed between said end castings, and means for connecting said separate sill members to said end castings, certain of said separate sill members being connected to said end sill and cross bearer in spaced relation outwardly of said pedestal sills.

bearer and end sill, journal pedestals on said pedestal sills, said castings having members extending laterally of said cross bearer substantially in alignment with said draft and pedestal sills and said cross bearer and end sill extending laterally outwardly of said pedestal sills, and a

plurality of separate sill members extending between and connected to said first-named members and to said cross bearer and end sill extensions.

WILLIAM C. HEDGCOCK.
ROBERT B. COTTRELL.
